HARRY R. HOLBROOK, OF ATTLEBORO, MASSACHUSETTS.

AUTOMATIC VENDING-MACHINE.

No. 872,624.

Specification of Letters Patent.

Patented Dec. 3, 1907.

Application filed September 22, 1905. Serial No. 279,700.

To all whom it may concern:

Be it known that I, HARRY R. HOLBROOK, a citizen of the United States, residing at Attleboro, in the county of Bristol and State 5 of Massachusetts, have invented a new and useful Improvement in Automatic Vending-Machines, of which the following is a specification.

This invention has reference to an improvement in automatic vending machines and more particularly to an improvement in the actuating mechanism of automatic vending machines.

The class of automatic vending machines 15 to which my invention is particularly applicable requires only that the buyer shall insert a coin in the slot, when the merchandise will be delivered automatically to an open compartment from which the merchandise 20 can be easily removed by the buyer.

The object of my invention is to improve the construction of an automatic coin controlled vending machine whereby the delivery of the merchandise by fraudulent manipulation is prevented and the operation of the actuating mechanism is more certain than has heretofore been attained.

My invention consists in the peculiar and novel construction of a coin controlled vending machine comprising a case having a top in which are coin slots, a glass front, and a base having a closed coin receptacle and an open compartment through which the merchandise is delivered, coin chutes adapted to 30 have a vertical reciprocating movement in the case, merchandise delivery hoppers in the case, actuating mechanism on the hoppers adapted to engage with a finger on the adjacent coin chute whereby on the dropping 35 of a coin through the coin slot and chute the actuating mechanism is operated to automatically deliver one piece of merchandise from a hopper to the open compartment in the base, means in the actuating mechanism 40 of the hoppers to prevent fraudulent removal of the merchandise from the hopper, and details of construction, as will be more 45 fully set forth hereinafter.

Figure 1 is a front view of my improved 50 automatic vending machine, showing the coin slots, the merchandise in the hoppers and the open compartment through which the merchandise is delivered. Fig. 2 is a vertical sectional view taken on line 2 2 of 55 Fig. 1, showing the construction of the machine with the actuating mechanism in its

normal position. Fig. 3 is an enlarged detail view looking at the back of a merchandise hopper and showing the actuating mechanism in its normal position. Fig. 4 is an enlarged detail sectional view taken on line 4 4 of Fig. 3, showing the actuating mechanism in its extreme operative position in full lines and in its intermediate position in heavy dotted lines. Fig. 5 is a transverse sectional view taken on line 5 5 of Fig. 3 through the merchandise hopper and actuating mechanism. Fig. 6 is a transverse sectional view taken on line 6 6 of Fig. 3 through the hopper, actuating mechanism, and part of the 70 coin chute, and Fig. 7 is a transverse sectional view taken on line 7 7 of Fig. 4 through the coin chute.

In the drawings, *a* indicates the case, *b* the coin chutes, *c* the merchandise delivery 75 hoppers, *d* the automatic actuating mechanisms on the back of the hoppers, *e* the merchandise in the hoppers, and *f* a coin shown in broken lines in Fig. 2 to illustrate the operation of my improved automatic 80 vending machine.

The case *a* is constructed to have the base *a'* in which is the open compartment *a²* and the coin receptacle *a³*, the base top *a⁴* in which is the opening *a⁵* and the slot *a⁶*, the 85 back *a⁷* supporting the lower bracket *a⁸* in which is the slot *a⁹* for the coin chute and the upper bracket *a¹⁰* having the slot *a¹¹* for the coin chute and the opening *a¹²* for the merchandise, the sides *a¹³ a¹³* the glass front *a¹⁴*, 90 and the top *a¹⁵* having the raised back portion *a¹⁶* in the vertical front of which are the coin slots *a¹⁷ a¹⁷*, as shown in Figs. 1 and 2.

The coin chutes *b* are constructed in the form of a flattened tube in one side of which 95 is the slot *b'*, as shown in Fig. 7. Each chute has the opening *b²* in the edge adjacent the actuating mechanism *d* and the outwardly-curved upper end *b³*, as shown in Fig. 2. A coiled spring *b⁴* is secured at one 100 end to the chute and at the other end to the bracket *a¹⁰*, the tension of the spring holding the coin chute in its normal or raised position, with the lower edge of the curved end *b³* above the lower edge of the coin slot *a¹⁷*, 105 and a hook-shaped finger *b⁵* secured to the edge of the chute adjacent the opening *b²*.

The merchandise hoppers *c* are each constructed in the form of an open ended rectangular tube having the slot *c'* in its front 110 for displaying the merchandise, the stamped-up lugs *c² c²* and *c³ c³* on the back, the stops

$c^4 c^4$ and $c^5 c^5$, the two apertures $c^6 c^6$ adjacent the stops $c^5 c^5$, and the central opening c^7 , as shown in Figs. 3 and 4. The hoppers $c-c$ are each secured at their lower ends to the base 5 top a^4 over the openings $a^5 a^5$ and at their upper ends to the bracket a^{10} under the openings $a^{12} a^{12}$, as shown in Fig. 2.

The actuating mechanism d comprises a latch d' pivotally secured near its center to 10 the lugs $c^2 c^2$ on the back of the hopper c , and having the downwardly-extending lower arm d^2 , the two outwardly-extending central arms $d^3 d^3$ supporting the cross bar d^4 and the upwardly-extending arm d^5 on the end of 15 which are the ears $d^6 d^6$, as shown in Figs. 4 and 5. A catch d^7 having the hook-shaped end d^8 and the weighted portion d^9 is pivotally secured to the arm d^2 of the latch in a position for the hook-shaped end d^8 to enter 20 the opening c^7 in the back of the hopper c . A yoke d^{10} having the forwardly-extending side arms $d^{11} d^{11}$, the rearwardly-extending L-shaped arm d^{12} , and the upwardly-extending arm d^{13} is pivotally secured by the side 25 arms $d^{11} d^{11}$ to the ears $d^6 d^6$ on the arm d^5 of the latch. An arm d^{14} is pivotally secured to the ears d^6 in a position to enter the aperture c^6 in the back of the hopper, as shown in 30 Figs. 4 and 5. A whip spring d^{15} is secured to the lugs $c^3 c^3$ on the back of the hopper in a position for the free end of the spring to bear on the arm d^{13} of the yoke d^{10} , as shown in Fig. 4. The arms $d^{11} d^{11}$ and the arm d^{14} act through the apertures $c^6 c^6$ as stops to hold 35 the merchandise e in the hoppers. The actuating mechanism d is attached to the back of a hopper c in a position for the finger b^5 on the coin chute to engage with the cross bar d^4 on the latch and for the L-shaped arm d^{12} 40 on the yoke d^{10} to enter the opening b^2 in the coin chute, as shown in full lines in Fig. 4.

The merchandise e may be the article to be vended or a circular box inclosing the article.

45 In the operation of my improved automatic vending machine the buyer enters a coin in a coin slot a^{17} . The peripheral edge of the coin engages with the upper edge of the coin slot and with the lower edge of the upper end of the coin chute b , as shown in 50 broken lines in Fig. 2. A slight push on the coin in entering the coin chute now moves the coin chute downwards against the tension of the coiled spring b^4 , into the position, 55 as shown in full lines in Fig. 4. This downward movement of the coin chute brings the finger b^5 on the coin chute into engagement with the cross bar d^4 on the latch d' and moves the actuating mechanism d into its extreme operative position against the tension 60 of the whip spring d^{15} . This extreme operative position of the actuating mechanism draws the arms $d^{11} d^{11}$ and d^{14} (which acts as stops on the merchandise) out of the apertures $c^6 c^6$ in the back of the hopper and moves the

hook-shaped end d^8 of the catch d^7 through the opening c^7 into the hopper, thus allowing one of the articles of merchandise e to drop onto the hook-shaped end d^8 of the catch, as shown in full lines in Fig. 4. The instant a 7 coin has entered the coin chute, the chute is returned to its raised or normal position by the tension of the coiled spring b^4 . The tension of the whip spring d^{15} on the yoke d^{10} now moves the actuating mechanism into its 75 intermediate position, with the ends of the arms $d^{11} d^{11}$ resting on the back of the hopper against the stops $c^4 c^4$, the arm d^{14} extending through an aperture c^6 and under the adjacent article of merchandise and the hook-shaped end d^8 of the catch still holding the article of merchandise to be delivered, as shown in heavy dotted lines in Fig. 4. The coin now dropping down the chute strikes the L-shaped arm d^{12} on the yoke (which extends into the opening b^2 in the chute) and moves the arms $d^{11} d^{11}$ on the yoke against the stops $c^3 c^3$ on the back of the hopper. The tension of the whip spring d^{15} now moves the actuating mechanism d into its normal 80 position, as shown in Fig. 2. This moves the arms $d^{11} d^{11}$ and d^{14} through the apertures and under the following article of merchandise and moves the hook-shaped end d^8 of the catch out of the hopper, thus allowing the 85 article to drop through the opening a^2 from which it can be readily removed by the buyer. By this construction and operation of the mechanism all of the articles of merchandise in the hopper are positively locked against fraudulent manipulation and the article to be vended is only released by the actual striking of the coin on the arm d^{12} on the yoke d^{10} in its 90 passage down the coin chute. 100

Having thus described my invention, I claim as new and desire to secure by Letters Patent;—

1. An automatic vending machine comprising a case in which is a coin slot, an open 110 compartment, a coin receptacle, a coin chute adapted to have a reciprocating movement, a merchandise hopper, actuating mechanism on the hopper the normal position of which locks the merchandise in the hopper, said actuating mechanism consisting of a latch 115 pivotally secured near its center to the hopper, a weighted catch pivotally secured to the lower end of the latch and adapted to enter the hopper, a yoke pivotally secured to the upper end of the latch and having fixed arms and a pivoted arm adapted to enter the hopper and an arm adapted to enter an opening in the coin chute, a whip spring secured to the hopper in a position to exert a 120 spring tension on the yoke, and a finger on the coin chute adapted to engage with the latch of the actuating mechanism, whereby on the entering of a coin through the coin 125 slot into the coin chute the actuating mech- 130

anism first assumes an extreme operative position to partly release the bottom article of merchandise, then an intermediate position to lock the following articles of merchandise, and then its normal position to fully release the bottom article of merchandise from the hopper, as described.

2. The combination with an automatic vending machine having a case *a* in which is 10 an open compartment *a*², a coin receptacle *a*³, a coin slot *a*¹⁷, a coin chute *b* having an opening *b*² and held in its normal position by a coiled spring *b*⁴, and a merchandise hopper *c*, of an actuating mechanism *d* comprising a 15 latch *d*' pivotally secured to the back of the hopper *c* and having the lower arm *d*², the central arm *d*³ *d*³ supporting the cross bar *d*⁴, and the upper arm *d*⁵ on the end of which are the ears *d*⁶ *d*⁶, a catch *d*⁷ having the hook-shaped end *d*⁸ and the weighted portion *d*⁹ pivotally secured to the end *d*² of the latch *d*' in a position for the hook-shaped end *d*⁸ to 20 enter an opening in the hopper *c*, a yoke *d*¹⁰ having the side arms *d*¹¹ *d*¹¹, an L-shaped arm *d*¹², an upper arm *d*¹³, a pivoted arm *d*¹⁴, and pivotally secured to the ears *d*⁶ *d*⁶ on the arm *d*⁵ of the latch *d*' in a position for the arms *d*¹¹ *d*¹¹ and *d*¹⁴ to enter openings in the hopper *c*, and the L-shaped arm *d*¹² to enter the 25 opening *b*² in the coin chute *b*, a whip spring *d*¹⁵ secured to the hopper *c* in a position for the free end of the spring to bear on the arm *d*¹³ of the yoke *d*¹⁰, and means for operatively connecting the coin chute *b* with the latch *d*' 30 whereby on the entering of a coin through the coin slot *a*¹⁷ into the coin chute *b* the actuating mechanism *d* first assumes an extreme operative position to partly release the bottom article of merchandise in the hopper, 35 then an intermediate position to lock the following articles of merchandise in the hopper, and then its normal position to fully release the bottom article of merchandise from the hopper, as described.
3. An automatic vending machine, embodying a case, a movable coin chute, a merchandise hopper, actuating mechanism on the hopper the normal position of which locks the merchandise in the hopper, embodying a latch pivoted to the hopper, a catch pivoted to the lower end of the latch and adapted to enter the hopper, a member pivoted to the upper end of the latch embodying a pivoted arm adapted to enter the 45 hopper and an arm adapted to enter an opening in the coin chute, said member being spring pressed, and a finger on the coin chute adapted to engage with the latch whereby on the entering of a coin the actuating mechanism first assumes an extreme operative position to partly release the bottom article of merchandise, then an intermediate position to lock the following articles, and finally its 50 normal position to fully release the bottom article.

4. A vending machine embodying a merchandise hopper, a coin actuated vertically depressible coin receiving chute disposed adjacent said hopper and spaced therefrom, said hopper and chute having openings in adjacent sides, means to control the discharge of the merchandise in said hopper disposed in said space between the hopper and chute and adapted to project in said openings of the hopper and chute, and a projection on 70 said chute adapted on downward movement of the chute to engage and operate said means.

5. A vending machine comprising a merchandise hopper, a suspended coin chute 80 adapted for movement with relation thereto said article chute having upper and lower openings therein, an article delivery controlling mechanism comprising an upper finger normally disposed within said upper opening 85 and a lower finger normally held out of said lower opening means actuated upon the movement of said coin chute in a determinate direction for moving the upper finger out of said upper opening and for simultaneously moving the lower finger into said lower opening, coin actuated means for moving said lower finger out of said lower opening after the actuation of said first named means means for restoring said upper finger and the 90 actuating means therefor to normal position after the actuation of said coin actuated means, and means for restoring said coin chute to normal position.

6. A vending machine comprising a merchandise hopper a spring held suspended coin chute adapted for movement with relation thereto, said merchandise hopper having upper and lower openings therein, an article delivery controlling mechanism comprising an 100 upper finger normally disposed within said upper opening and a lower finger normally held out of said lower opening, means actuated upon the movement of said coin chute in a determinate direction for moving the upper 105 finger out of said upper opening and for simultaneously moving the lower finger into said lower opening, a member having a side arm constituting a pawl pivoted adjacent said upper finger and having a portion normally out of but adapted to be projected into the path of the coin in said coin chute, said upper finger in its movement out of said upper opening moving said pawl into position whereby it engages said hopper as a stop, 110 said finger also moving said projecting portion into the path of said coin in said coin chute, said coin being designed to engage said projecting portion and move the same to disengage said pawl from said stop, a 115 spring designed upon disengagement of said pawl to restore said fingers and the actuating means therefor to initial position.

7. A vending machine comprising a merchandise hopper, a suspended coin chute 120

- adapted for movement with relation thereto, oppositely movable upper and lower fingers designed for movement through said article chute, said upper finger being normally within said hopper and said lower finger being normally without the same, means actuated on the movement of said coin chute for reversing the normal relation of said fingers, means for sustaining said fingers in such related 5 relation, coin actuated means for releasing said sustaining means, means for restoring said fingers to normal position after the operation of said coin actuated means and means for restoring said coin chute to 10 initial position.
8. A vending machine embodying a merchandise hopper, and a movable coin chute disposed in spaced relation, said hopper and coin chute each having side openings, means 15 for discharging the merchandise having portions adapted to move into and out of said openings of the hopper and the chute, and means on the chute to engage said discharging means and operate the same upon movement of the chute.
9. A vending machine embodying a vertical merchandise hopper and a vertical down-

wardly movable coin chute arranged in spaced relation and each having an opening formed in their adjacent sides, pivoted merchandise discharging means having parts adapted to project in each of said openings, and cooperating means between said chute and said discharging means whereby upon downward movement of the chute said discharging means will be actuated.

10. A vending machine embodying a merchandise hopper and a movable coin chute, said hopper and chute each having side openings, movable merchandise discharging means 40 having a plurality of parts some of which are adapted to enter said openings of the hopper and chute, and means on the chute adapted upon movement of the chute to engage another of said parts of the discharging means 45 and thereby operate the latter.

In testimony whereof I have signed my name to this specification in the presence of two subscribing witnesses.
